UNITED STATES PATENT OFFICE.

GUSTAF A. STARK, OF ATWATER, MINNESOTA.

GRAVE COVERING AND LINING DEVICE.

Application filed July 25, 1927. Serial No. 208,195.

This invention relates to grave covering and lining devices.

It is the object of this invention to provide certain improvements on the grave covering and lining devices illustrated and claimed in my two pending U. S. applications for patent entitled "Grave covering and lining device" and "Grave lining and covering device," respectively, Serial Numbers 148,348 and 10 148,349, respectively, filed November 15, 1926.

It is more specifically the object of this invention to provide the combination with a casket lowering device including side rollers, of means adapted normally to extend over a grave to conceal the same and pawl and ratchet mechanism for connecting said means with said rollers to operate the same from said rollers as a casket is lowered into the grave by said device and to swing said means downwardly into the grave to line the walls of the same and to permit continued rotation of the rollers in respect to said means after the walls of the grave have been lined thereby.

A further object is to provide the combination with a casket lowering device of means adapted to be swung downwardly into a grave as a casket is lowered therein by said device, shrouds extending over said means to line the walls of the grave as said means are downwardly swung, and apparatus for so positioning said shrouds that the same will not interfere with the action of the lowering device.

These and other objects and advantages of the present invention will more fully appear from the following description made in connection with the accompanying drawings, wherein like reference characters refer to the same or similar parts throughout the various views and, in which,

Fig. 1 is a plan view showing the application of one embodiment of the present invention to a standard casket lowering device, certain of the parts being broken away and certain of the parts being shown in section;

Fig. 2 is a vertical section taken on the line 2—2 of Fig. 1, as indicated by the arrows, certain of the parts being broken away and certain of the movable parts being illustrated in full lines in one position and in dotted lines in another position;

Fig. 3 is a vertical section taken on the line 3—3 of Fig. 1, as indicated by the arrows, with the end shroud removed from the device;

Fig. 4 is an enlarged view similar to Fig. 2

of certain of the parts of the device with portions thereof broken away;

Fig. 5 is a vertical section taken on the line 5—5 of Fig. 4, as indicated by the arrows; 60

Fig. 6 is a plan view of a type of pawl that may be used, certain of the parts being broken away;

Fig. 7 is a vertical section taken on the line 7—7 of Fig. 1, as indicated by the arrows; 65

Fig. 8 is a plan view showing one of the end shrouds detached from the device; and

Figs. 9, 10 and 11 are detail views of certain of the parts of the device.

Referring to the drawings, a casket lowering device of standard construction is illustrated including corner posts 12, side shafts or rollers 13, end shafts 14 and webbing straps 15 extending between the side rollers 13 and

having their ends detachably secured thereto by clips 16. A foot control pedal 17 is used for controlling the lowering of the device and a crank 18 for winding up the ends of the webbing straps 15 on the side rollers 13 before or after using the device. The lowering device is of substantially rectangular 70

shape and is adapted to be set up and situated over an open grave, whereupon a casket such as the casket 19 may be placed on the webbing straps 15 and the foot control pedal 17 may be pressed downwardly to permit the weight 75

of the casket to carry the same downwardly into the grave, the rollers 13 rotating towards each other as the casket sinks into the grave to pay out the webbing straps. 80

In accordance with the present invention, a rectangular frame is provided which is adapted to be placed to rest on the ground immediately surrounding the device. This frame is of tubular construction and preferably consists of corner side tubes 20, corner 85

end tubes 21, medial side tubes 22, medial end tubes 23 and sockets 24 connecting respective corner side and end tubes. The corner side tubes 20 are adapted to telescope within the medial side tubes 22 to permit longitudinal adjustment of the frame, while the corner end tubes 21 are adapted to telescope within the medial end tubes 23 to permit transverse adjustment of the frame. The 90

sockets 24, as best illustrated in Fig. 11, are preferably threaded to the ends of the corner end tubes 21 and are apertured to receive the corner side tubes 20. Set screws 25 are provided in sockets 24 to hold the corner side tubes 20 from movement after the same have 95

been placed in a desired adjusted position. 100

105

110

If desired, other types of frame construction may be used.

The corner side tubes 20 have vertical apertures 20^a extending therethrough adapted to 5 receive pin portions 26^a of vertical arms 26. The said arms have enlarged portions 26^b above the pin portions thereof and are provided at their upper ends with apertured heads through which the rods 27 extend. 10 Rods 27 stand at a level slightly above the level of side rollers 13 of the lowering device, extend parallel to the sides of the rectangular frame above described and have telescopic connection with sleeves 28 to permit lengthwise adjustment of the side frames formed by arms 26, rods 27 and sleeves 28.

A pair of ratchets 29 are fixed by set screws to each of the side rollers 13 outwardly from the webbing straps 15. The said ratchets 20 have a series of teeth thereon, arranged symmetrically in respect to radii of the ratchets. Flanges are provided at each side of the ratchets to provide hubs therefor. Two wings preferably are provided, one of which 25 is adapted to be mounted on each of the side rollers 13. Each wing comprises two end arms 30, extensions 31 having apertured heads at their inner ends, rods 32 extending through said apertured ends of extensions 31 30 and a sleeve 33 within which the central ends of rods 32 are adapted to telescope. The outer ends of arms 30 are hook shaped and are of channel shape in cross section to embrace the flanged hubs of ratchets 29, the 35 ratchets extending between the sides of the channel portions thereof and the flanges of the ratchets projecting at either side of the ends of the arms. Each arm 30 has a partition 30^a closing the inner portion of the channel formed therein and inwardly from partition 30^a the arm is of hollow squared construction in cross section to receive the squared extension 31 and to hold the same in any desired outwardly extended position by 40 means of set screws 34. A pawl holder 35 is pivoted adjacent the inner end of the channel formed in arm 30 and is provided with a shoulder at its lower side against which the lower end of a curved bar or equivalent 45 spring 36 contacts, the said bar spring bearing against the partition 30^a and against the lower side of the medial portion of the channel formed in arm 30. Holder 35 is provided with a threaded aperture 35^a within which 50 the threaded shank portion of a pawl 37 is secured. The pawl 37 is rabbeted at its blade end as best shown in Fig. 6, and a band 38 of resilient material such as elastic is glued or otherwise secured to the rabbeted portion of 55 the blade of the pawl. The pawl will normally be held in engagement with one of the teeth of ratchet 29 by the spring 36. A latch plate 42 having a free end of arcuate shape is 60 pivoted at its other end to the arm 30 and is 65 adapted to be swung to engage with one of

the projecting side flanges of ratchet 29 to retain the ratchet in position within the hook shaped bearing portion of the arm.

Side shrouds designated by the numeral 70 39 are secured by hooks 40 to the side tubes 20 and 22, are then extended upwardly over rods 27 and 28 of the side frame and are extended over the side rollers 13 and the wings formed by arms 30, extension 31, rods 32 and sleeves 33 and are then allowed to depend downwardly from the wings into the grave. The shrouds 39 are preferably formed from some type of flexible material such as canvas or artificial grass matting and are provided with slits 39^a through which the webbing straps 15 are extended. End shrouds 41 having slots 41^a at the sides thereof communicating with apertures 41^b are secured by hooks 40 to end tubes 21 and 23 and to the extreme end portions of the side tubes 20. The end shrouds are then extended upwardly over the corner posts 12 of the lowering device and are allowed to depend downwardly from the corner posts into the grave to line the end walls thereof, the side rollers 13 being received within apertures 41^b of the end shrouds.

Considering the parts of the device to be situated as illustrated in full lines, Figs. 1, 2 and 3, the grave and all parts of the lowering device will be concealed by the shrouds 39 and 40 with the exception of the central portions of the webbing straps 15. The device is now ready for use at a burial ceremony. The casket 19 is placed on the webbing straps 15, whereupon the foot pedal 17 is downwardly pressed. The weight of the casket will carry the same downwardly into the grave causing the webbing straps 15 to be unwound from rollers 13 and causing the rollers 13 to rotate towards each other. As the pawls 37 are in engagement with the teeth of the ratchet 29 and as the major portion of the wings formed by arms 30, extensions 31, rods 32 and sleeves 33 are extended inwardly from the rollers 13, the weight of the wings will cause the same to be swung downwardly into the grave as the rollers 13 are rotated. The downward swinging movement of the wings will continue until the extensions 31 strike the side walls of the grave, whereupon as the casket is further lowered into the grave, continued rotation of rollers 13 in respect to the wings will be permitted due to the fact that succeeding teeth on ratchet 29 will swing pawls 37 outwardly against the tension of springs 36 to permit the ratchets 29 to rotate in respect to the pawls. The resilient bands 38 on the blade ends of pawls 37 will cushion blade portions of the pawls against the teeth of the ratchets to prevent objectionable clicking noises as the pawls spring back against the teeth of the ratchets. As the wings are swung downwardly the shrouds 39 resting thereover will also be carried 95 100 105 110 115 120 125 130

downwardly from a position indicated in full lines, Fig. 2, to the position indicated in dotted lines, Fig. 2, thereby causing the shrouds to line the side walls of the grave. The end shrouds 41 line the end walls of the grave so that after the casket has been lowered, all the walls of the grave will be completely lined to present an attractive appearance and to cover up all view of the bare earth.

10 After the casket has been completely lowered and the webbing straps released from the casket, the wings and side shrouds may be raised as the crank 18 of the lowering device is turned, inasmuch as the springs 36 will 15 hold the pawls 37 against the ratchets 29 causing the wings to be upwardly swung as the side rollers 13 are reversely rotated.

After use at a burial ceremony, the grave covering and lining device can be quickly dis- 20 assembled and packed in small compass for transportation or storage. The shrouds 39 and 41 can be quickly unhooked from various tubes to which they are connected. The main rectangular frame and the side frames 25 may be readily taken apart and the wings can be unhooked from the side rollers 13 and disassembled. The ratchets 29 will be removable from the lowering device after latches 42 have been disengaged from the flanges of 30 the ratchets. Due to the fact that the frames and the wings are adjustable both longitudinally and transversely, the grave covering and lining device may be adjusted for use on different sized lowering devices.

35 To fix the wings in proper position for use, the arms 30 are hooked over the ratchets so that the ratchets will be embraced between the sides of the channel portions of the hooked ends of the arms and the hubs formed 40 by the flanges on the sides of the ratchets will be bearinged on the edges of the sides of the hooked channeled portions. The wings are then swung upwardly and the pawls 37 are adjusted in sockets 35 until they are of 45 the proper length to engage the ratchet teeth of ratchets 29 and hold the wings disposed inwardly from the rollers 13 over the grave in substantially a horizontal plane. When the wings are so disposed with the webbing 50 straps 15 tightly wound up, the wings will be positively held and cannot sag and the side shrouds supported by the two wings will present an attractive even surface. The top edge of the end shrouds 41 will stand at about 55 the same height as the side shrouds so that the top surface of the lining and covering device will present practically an unbroken appearance.

60 The apertures 41^b in the end shrouds 41 are elongated so that the same end shrouds may be used when the width of the grave covering and lining device is varied. When the length of the device is shortened, the sides 65 of the side shrouds 39 may be depended

downwardly from the ends of the wings. Due to the fact that the side shrouds 39 are supported from the side frames at a level above the level of the side rollers 13 before being extended over the wings, no binding 70 action will occur between the shrouds and the rollers as a casket is lowered into the grave.

The device is of simple and cheap construction and may be quickly set up or removed 75 from a lowering device. It has been successfully demonstrated in actual practice.

It will, of course, be understood that various changes may be made in the form, details, arrangement and proportions of the 80 various parts without departing from the scope of the present invention, which, generally stated, consists in the matter shown and described and set forth in the appended 85 claims.

What is claimed is:

1. The combination with a casket lowering device adapted to extend over an open grave and having side rollers rotatable towards each other, of means adapted normally to extend over the grave to conceal the same, and pawl and ratchet mechanism connecting said means with said rollers to permit said means to be swung downwardly by said rollers into the grave to line the walls of the same as a casket 95 is lowered therein by said device and to allow continued rotation of said rollers in respect to said means after said means have been downwardly swung.

2. The combination with a casket lowering 100 device adapted to extend over an open grave and having side rollers rotatable towards each other, of wings mounted on said rollers and adapted normally to extend over the grave, shrouds carried by said wings to normally conceal the grave, and pawl and ratchet mechanism connecting said wings with said rollers to permit said wings and said shrouds to be swung downwardly by said rollers into the grave to line the walls thereof as a casket 105 is lowered therein by said device, and to allow continued rotation of said rollers in respect to said wings after said wings have been downwardly swung.

3. The combination with a casket lowering 110 device adapted to extend over an open grave and having side rollers rotatable towards each other, of means adapted normally to extend over the grave to conceal the same, ratchets secured to said rollers and pawls mounted on said means to engage with said ratchets and permit said means to be swung downwardly by said rollers into said grave to line the walls thereof as a casket is lowered therein by said device and to disengage from said ratchets 115 to allow continued rotation of said rollers in respect to said means after said means have been downwardly swung.

4. The combination with a casket lowering 120 device adapted to extend over an open grave 125

- and having side rollers rotatable towards each other, of wings having hooks at their outer sides adapted to be hooked over said rollers and adapted to normally extend over said grave, shrouds carried by said wings to normally conceal the grave, and pawl and ratchet mechanism connecting said wings with said rollers to permit said wings and shrouds to be swung downwardly by said 10 rollers into said grave to line the walls of the same as a casket is lowered therein by said device and to allow continued rotation of said rollers in respect to said wings after said wings have been downwardly swung.
- 15 5. The structure defined in claim 3, said pawls being adjustable in length, whereby they may be engaged with various teeth of said ratchets when said ratchets are in normal fixed position when said lowering device is 20 in raised position, thereby permitting said means to be properly adjusted to be held in substantially a horizontal plane when in normal position.
6. The combination with a casket lowering 25 device adapted to extend over an open grave and having side rollers rotatable towards each other, of ratchets secured to said rollers and having flanges on their outer sides, arms of hook shape at their outer ends and of channel shape in cross section at their outer ends, the outer ends of said arms being hooked over said ratchets so that said ratchets will 30 extend within the channel portions thereof, pawls pivoted in said arms and adapted to be engaged with said ratchets to hold said arms extending inwardly from said rollers over the grave in substantially a horizontal plane when said lowering device is in raised position and to permit said arms to be swung 35 downwardly into the grave by said rollers as the same are rotated when a casket is being lowered into the grave by said device until said arms strike the walls of the grave, whereupon said rollers will be permitted to rotate 40 in respect to said arms, and shrouds carried by said arms and adapted to conceal the grave when said arms are in horizontal position and to line the sides of the grave when said arms are downwardly swung.
- 45 7. The combination with a casket lowering device adapted to extend over an open grave and having side rollers rotatable towards each other, of wings mounted on said rollers and adapted normally to extend over the grave, shrouds carried by said wings to normally conceal the grave, ratchets secured to said rollers and pawls pivoted in said wings and adapted to engage with said ratchets and permit said wings and shrouds to be carried 50 downwardly by said rollers into the grave to line the walls thereof as a casket is lowered therein by said device and to disengage from said ratchets to allow continued rotation of said rollers in respect to said wings after said 55 wings have been downwardly swung.
8. The structure defined in claim 7, each of said pawls comprising a holder portion pivoted to one of said wings and a blade portion carried in said holder portion and adjustable in length outwardly therefrom, whereby said pawls can be accurately adjusted in length to engage with one of several teeth of a ratchet held in fixed position when said lowering device is in raised position to permit said wings being accurately extended inwardly from said rollers in substantially a horizontal plane. 75
9. The structure defined in claim 2, and end shrouds extending downwardly into the ends of the grave to line the end walls thereof. 80
10. The combination with a casket lowering device adapted to be positioned over an open grave and having side rollers rotatable towards each other, of means adapted to be held normally in substantially a horizontal plane over an open grave when said lowering device is in raised position and adapted to be swung downwardly into said grave by said rollers to substantially a vertical position adjacent the grave walls as a casket is lowered 85 into the grave by said device, an annular frame surrounding said lowering device and adapted to rest on the ground, side frames extending upwardly from the sides of said first mentioned frame to a position above said rollers and shrouds secured to the sides of said first mentioned frame extending over said side frame and over said means into the grave, said shrouds being adapted to be carried by said means, whereby as a casket is lowered 90 into the grave said shrouds will be swung downwardly by said means without binding on said rollers to line the sides of the grave. 95
11. In combination with a casket lowering device having side rollers and adapted to extend over an open grave, means adapted to be held normally in horizontal position over said grave and to be swung downwardly into said grave to substantially vertical position adjacent the walls of said grave, an annular frame surrounding said lowering device and adapted to rest on the ground adjacent thereto, side supporting arms extending upwardly at each side of said first mentioned frame to a level above said rollers, rods connecting the 100 upper ends of said arms at each side of the lowering device and shrouds secured to the sides of said first mentioned frame extending over said side frames and into the grave and adapted to be carried downwardly by said 105 means to line the sides of a grave as a casket is lowered therein. 110
12. The structure defined in claim 7, springs pressing said pawls against said ratchets and resilient strips at the blade ends of said pawls for cushioning said pawls against said ratchets. 120
13. The combination with a casket lowering device adapted to extend over an open grave and having side rollers rotatable toward each 130

other, of means adapted normally to extend over the grave to conceal the same and means connected with said first mentioned means and adapted to be engaged with said side rollers 5 to carry said first mentioned means downwardly into the grave to cause the same to line the walls of the grave as said rollers are rotated in one direction and to permit continued rotation of said rollers in respect to 10 said first mentioned means after the walls of the grave have been lined and to engage with

said rollers as they are reversely rotated to cause said first mentioned means to be carried out of the grave.

14. The structure defined in claim 3, and 15 means normally holding said pawls against said ratchets to cause said pawls to be engaged with said ratchets as said rollers are reversely rotated to carry said first mentioned means out of the grave. 20

In testimony whereof I affix my signature.

GUSTAF A. STARK.
